UNITED STATES PATENT OFFICE

NEIL D. PRESTON, OF ROCHESTER, NEW YORK, ASSIGNOR TO GENERAL RAILWAY SIGNAL COMPANY, OF ROCHESTER, NEW YORK

AUTOMATIC TRAIN-CONTROL SYSTEM

Application filed September 10, 1924. Serial No. 736,929.

This invention relates to automatic train control systems for railroads, and more particularly to systems of the intermittent inductive type in which continuing speed restrictions are enforced under unsafe traffic conditions.

In accordance with this invention, it is proposed to automatically apply the brakes and stop the train, unless the engineer takes an appropriate action, conveniently termed acknowledgement, at each caution signal or corresponding control point, and also at each stop or danger signal. It is considered that the enforcement of such acknowledgement on the part of the engineer will serve to stimulate and maintain his vigilance, thereby assuring greater safety of train movement, inasmuch as failure of both the train control system and the engineer must occur before an accident can result. According to this invention, such acknowledgement is required at each successive stop signal.

According to this invention, the engineer is obliged to reduce the speed of his train, if necessary, after passing each caution signal, so as to be prepared to stop at the next signal or block entrance, otherwise an automatic application of the brakes occurs; and this requisite is satisfied in a simple and direct manner by requiring the engineer to initiate a brake application or have the brakes acting, if the speed is above some selected minimum speed.

Various other characteristic features, advantages, and specific objects of this invention will appear hereinafter as the description progresses.

In describing the invention in detail, reference will be made to the accompanying drawings, in which Fig. 1 shows in a simplified and diagrammatic manner the trackway equipment and locomotive equipment constituting one embodiment of the invention and adaptable for train movement on double track railroads, the parts and circuits being shown more with the purpose of facilitating explanation and understanding of the nature and character of the invention than with the idea of illustrating the construction and arrangement of parts that would probably be employed in practice; and Fig. 2 shows dia-

grammatically and in accordance with established invention the trackway equipment for an intermediate signal location on a single track railroad equipped with an automatic block signal system of the type commonly known as the absolute-permissive-block system.

Referring to Fig. 1 of the accompanying drawings, the track rails 1 are divided into track sections or blocks by insulated joints 2 in the usual way, one complete block E, with the adjacent ends of two other blocks D and F being shown. It is assumed for the purposes of explanation that each block will be at least as long as braking distance for the normal running speed on the railroad, and will include only one track circuit. The parts and circuits associated with each of these blocks will ordinarily be the same; but for simplicity in illustration there is shown in Fig. 1 only the equipment for the block E. Each block is provided with the well known normally closed track circuit, including a track relay 3 and a track battery 4. As shown, a relay 5 is included in series with the track battery 4, this relay being of suitable construction and serving its well known purpose of attracting its armature and closing a normally open front contact 6 upon the entrance of a train into the corresponding block.

This system of train control is preferably used in conjunction with trackway block signals. The particular type of block signal and its form of control circuits may be any one of the kinds well known in the art. Semaphore signals 7 are shown conventionally, without attempting to illustrate any particular form of control circuits, it being assumed that these signals will be of the usual three-position type and controlled accordingly.

The controlling influences or impulses for the automatic train control system are communicated or transmitted according to this invention by magnetic induction between trackway devices and receivers, the action taking place through an intervening air-gap and without physical contact. These controlling impulses are transmitted only at predetermined points along the trackway where the track devices are located, and the system of

this invention is accordingly of the intermittent inductive type.

The track device for bringing about automatic control, conveniently termed the initiating track device, is designated as a whole T and comprises a permanent magnet 8, made up of a suitable number of sections of a general U-shape, in this instance shown disposed horizontally between the track rails 1. Secured to the ends of this permanent magnet 5 are vertically disposed soft iron cores 9, which have lateral extensions 10 projected toward each other and affording a leakage path for the magnetic flux of said permanent magnet, said leakage path being of relatively 10 higher reluctance than the flux path through the receiver later to be described. The cores 9 have enlarged pole pieces at their upper ends and are wound with deflecting or neutralizing coils 11. The coils 11 are so wound 15 and connected that, when energized from a suitable battery or similar source of current, they create a magneto-motive-force opposing that of the permanent magnet 8 and tending to cause the magnetic flux of said magnet to 20 pass across the leakage extensions 10, rather than above and between the pole pieces of said cores. In other words, when the neutralizing coils 11 are energized, the permanent magnet 8 produces a very weak magnetic field above the track device; whereas with these coils on open circuit and deenergized, said permanent magnet produces an 25 active magnetic field above the track device 30 thru which the receiver on the passing locomotive or other vehicle must pass.

The initiating track devices T may be located at different points in the several blocks as desired; but the preferred arrangement consists in locating one such track device in each block at braking distance for the selected minimum speed in the rear of the insulated joints defining the exit end of that block. Such a track device T¹ is shown in 40 the block E. In the case of long blocks, or 45 under other circumstances as desired, in addition to the initiating track device near the exit end of each block, as just described, there may also be another initiating track device in that block at braking distance from the exit end thereof for the normal running 50 speed of trains. Such a track device T is shown in the block E. The initiating track device near the exit end thereof is employed 55 to stop a train short of the end of the block, if the next signal in advance is in the danger position, unless the engineer takes appropriate action. In other words, this track device, such as T¹, is employed to enforce 60 acknowledgement of each stop signal. The same track device may be used, if desired, to enforce acknowledgement of a caution signal and control the car equipment so as to compel a reduction in speed in obedience to the caution 65 signal; or a separate initiating track de-

vice, such as T, may be employed in each block as the cautionary device.

Associated with each block is a reset or restoring track device, which is located near the exit end of each block. This reset track device TR comprises a soft iron core, preferably in the form of the general U-shape and provided with enlarged pole pieces. On the legs or back yoke of this core is wound a coil 12, and when this coil is energized, a 70 magnetic field exists above the reset track device. For reasons which will appear hereinafter, in the particular form of the invention shown, the reset track device is located outside of one of the track rails and is disposed lengthwise of the track. 75

The initiating track devices T and T¹, and the reset track device TR for each block may have their respective controlling circuits governed in various ways, by line relays, 85 track relays, or circuit controllers on the associated block signals. In order to economize in battery consumption, arrangements are shown such that the coils 11 and 12 of these track devices are normally deenergized 90 and are automatically energized upon the approach of the train.

The energizing circuit for the reset track device TR may be traced as follows:—commencing at the coil 12, wire 13, armature 6 of relay 5 and its front contact, wire 14, front contact 15 of the track relay 3 of the block next in advance, wire 16, battery 17 and wire 18. 95

The energizing circuit for the neutralizing 100 coils 11 of the caution track device T may be readily traced on the drawings and includes a battery 19 and the front contact 20 of a relay 21. The energizing circuit for the relay 21 includes a back contact 22 of the track relay 3 of block in which said track device is located and a front contact 23 of the track relay 3 of the next block in advance. 105

The other or stop signal initiating track device T¹ has an energizing circuit for its 110 neutralizing coils 11 which may be traced as follows:—commencing at coil 11, wire 24, front contact 6¹ of relay 5, wire 25, front contact 26 of track relay of block next in advance, wire 27, battery 28, and wire 29 back 115 to the coils 11.

The locomotive or other railroad vehicle is shown diagrammatically as two pairs of wheels and axles 30. Operated by one of these axles is an automatic reversing switch X, which in the simplified form shown comprises a pivoted switch arm 31 coupled by a link 32 to the outer end of a swinging arm 33 mounted to turn freely on the axle 30. A friction shoe 34 is carried by said arm 33 and is pressed against the axle 30, or a collar thereon, by a compression spring 35, thereby forming a frictional connection between the arm 33 and the axle. In Fig. 1 the normal direction of traffic is from left to right as 120 125 130

indicated by the arrow; and assuming a train movement in this direction, it will be evident that the arm 33 is moved by friction, as the axle turns, to the upper position shown. If 5 the locomotive should back up, or should run in the normal direction of traffic with the other end ahead, the reversing switch X would be operated to the other position, shifting the switch arm 31 to its lower position.

10 Suitably supported on the locomotive is a receiver R disposed in position to cooperate with the initiating track devices T and T¹. The receiver R, in the simplified construction shown, comprises two enlarged pole pieces or 15 collector plates 36, with extensions separated by an air-gap; and a pivoted armature 37 spans this air-gap, said armature being held in a retracted position by a suitable spring 38. This armature 37 carries a suitable 20 contact arranged to engage an insulated stationary contact, shown conventionally as an arrow, when said armature is in its retracted position. It will be evident that, when the receiver R passes thru the magnetic 25 field of an active track magnet T or T¹, the magnetic field of this track magnet will be collected by the pole pieces 36 and concentrated across the air-gap of the armature 37, thereby attracting this armature in opposition 30 to the spring 38 and opening its contacts.

In the particular form of the invention shown two receivers RR are employed, one on each side of the locomotive in position to pass over the reset track device or magnet TR. 35 These reset receivers RR are constructed alike, substantially the same as the receiver R, having a normally spring retracted armature 39. The contacts of the armature 39 of the reset receivers, however, are normally open and are closed by the attraction of this armature.

The locomotive or car equipment includes a plurality of relays P, S and Q of suitable construction, which are preferably quick acting, protected by spring supports against operation by vibration, and otherwise constructed in accordance with recognized practice so as to be adapted for their respective duties. The car equipment also includes a suitable speed responsive device or governor G, connected to and driven from the car wheels and acting to open contacts 40 whenever the speed of the car is above some selected minimum speed, such as fifteen or twenty miles per hour. This speed responsive device G may be of any suitable construction and is shown in a simplified manner as being of the well known centrifugal type.

60 It is assumed that the automatic application of the brakes will be produced by a suitable application valve or equivalent means, presumably controlled by an electro-pneumatic valve. The particular type of brake applying means is not material to the present invention and has not been illustrated. A

conventional form of electro-pneumatic valve EPV has been shown to illustrate the manner of control for the brake applying means.

It is assumed that this system of train control will be applied to a locomotive or other railway vehicle equipped with the usual air brake system, including an engineer's brake valve BV (shown in a simplified manner) which is equipped with contacts 41 which are closed only if the brake valve is in the service position, and also, if desired, in the emergency position. In conjunction with this system as herein disclosed it is necessary to have a circuit controlling device which closes contacts after a predetermined brake application has been effected so far as manual control is concerned. Such a device is shown in a simplified and diagrammatic manner and comprises two diaphragms 42 and 43 closing the ends of enclosed chambers 44 and 45. 70 In the chamber 44 and acting against the diaphragm 42 is a spring 46 having a strength corresponding to about 20 pounds per square inch on the diaphragm 43, a 20 pound reduction being assumed as constituting the desired brake application. The diaphragms 42 and 43 are connected by member 47 which, by the action of an insulated projection or equivalent means, acts to close contacts 48 when these diaphragms are shifted to the left in opposition to the spring 46. The chamber 44 is in communication with the regular equalizing reservoir of the air brake system; whereas the chamber 45 is in communication with the low pressure side of the feed valve, so that the pressure in this chamber 45 corresponds with the normal running brake pipe pressure. After the engineer makes a predetermined reduction in the equalizing reservoir pressure, assumed to be 20 pounds in 80 this instance, the pressure in the chamber 45 overcomes the reduced pressure in chamber 44 plus that of the spring 46, and shifts the diaphragms and their connecting member 47 to the left, thereby closing the contacts 48. The engineer may make the reduction in one or more stages. The contacts 48 do not close until a reduction has been made in equalizing reservoir pressure which in time will bring about a brake application of the desired effectiveness.

100 The act of acknowledgement hereinbefore mentioned has been taken to consist in manual operation of a suitable push button or contactor. This acknowledging contactor AC is located at a convenient point in the cab and readily accessible to the engineer. In the form shown, this acknowledging contactor comprises a plunger 49 and two contacts or switch arms 50 and 51. The plunger 49 is urged to its upper position by a spring 52. When this plunger is depressed by the engineer in opposition to the spring 52, the contact arm 50 is moved at once into engagement with a stationary contact, shown as an 105 110 115 120 125 130

arrow. The other contact arm 51 is released by such downward movement of the plunger 49, but its downward movement, brought about by an auxiliary spring 53, is retarded by a suitable dash-pot device 54, so that the resilient finger 55 of said contact arm 51 is not moved far enough to be disengaged from its cooperating contact (shown as an arrow) until after the plunger 49 has been held in the depressed position for a short interval of time, such as five or six seconds. The arm 51 returns quickly to its upper position.

In case the engineer fails to take appropriate action at each caution signal, or corresponding control point, or at each stop signal, it is desired to inflict some form of penalty in order that the engineer may be obliged to remain alert. Such penalty may take various forms, but in the arrangement shown, the train must be brought to a stop and the apparatus restored by operation of a reset switch RS which is accessible only from the ground. The reset switch RS comprises a push button or plunger 56 with normally closed contacts 57 and normally open contacts 58.

Operation.—The parts and circuits of the car equipment are shown in Fig. 1 in the normal position. The circuits have been shown in a simplified manner, embodying the symbols B and C to indicate the terminals of a car battery, turbo-generator, or other suitable source of current; and the circuits will be traced from B to C. The primary relay P is maintained energized by a stick circuit as follows:—commencing at B, front contact 60 of relay P, wires 61 and 62, relay P, wire 63, armature 37, and its contact to C.

The relay S is maintained energized by a stick circuit which may be traced as follows:—commencing at B, front contact 64 of relay S, wires 65 and 66, relay S, wire 67 and front contact 68 of relay P to C.

The relay Q is energized by a stick circuit which may be traced as follows:—commencing at B, front contact 69 of relay P, wires 70 and 71, timed contacts 55—51 of acknowledging contactor AC, wires 72, 73, front contact 74 of relay S, wires 75, 76, relay Q, wires 77 and 78, and front contact 79 of relay Q to C.

With the relay Q energized, the electro-pneumatic valve EPV is maintained energized by a circuit commencing at B through front contact 80 of relay Q, wire 81, valve EPV, wire 82 and normally closed contacts 57 of the reset switch RS to C.

Entering caution block.—Assuming the car equipment in the normal position shown, with the relays P, S and Q energized as just described, suppose that the car passes into a caution block, that is, a block next in the rear of an occupied block. For instance, assume a train in the block F, making the block E a caution block. As the following car or

train enters the block E, the track relay 3 is shunted and closes its back contact 22, but the relay 21 cannot be energized, because the front contact 23 of the track relay 3¹ of the block F is open. Consequently, the deflecting or neutralizing coils 11 of the track magnet T are on open circuit, and an active magnetic field exists over this track magnet. As the receiver R passes through this magnetic field, its armature 37 is attracted, interrupting the stick circuit for the relay P and causing its armature to be retracted and open its front contacts. The opening of the front contact 68 of the relay P breaks the stick circuit for the relay S, which is thereby deenergized and remains deenergized until restored by passing an active reset magnet. Upon deenergization of the relay S, the closure of its back contact 64 together with wire 83, establishes a connection to B in multiple with that through the front contact 60 of the relay P; and since the opening of the contacts of the armature 37 of the receiver R is only momentary, the relay P is quickly reenergized.

The opening of front contact 69 of the relay P, although only temporary, interrupts the stick circuit for the relay Q heretofore traced and would cause deenergization of this relay, unless at the time of the opening of said front contact 69, the engineer has the plunger 49 of his acknowledging contactor depressed so as to close the contacts 50 and establish a connection to B through these contacts and wire 84, in multiple with the connection to B through the front contact 69. In other words, unless the engineer takes the appropriate action by manually operating the acknowledging contactor AC, the relay Q is deenergized upon passing the active track magnet T, and the brakes are applied due to the resultant deenergization of the valve EPV. Also, the brakes will be automatically applied, in spite of such acknowledgement, if the running speed of the train is above the selected low speed limit, and the engineer has not initiated or completed a manual brake application, as hereinafter explained.

The timed contacts 55—51 protect the acknowledging contactor AC against abuse. If the engineer should attempt to fasten down the plunger 49, so as to avoid its repeated manipulation, the contacts 55 open after a time and interrupt the circuit for the relay Q, thereby applying the brakes. In short, the engineer must restore the acknowledging contactor AC to normal after each manipulation, otherwise the brakes are applied. The time interval provided for the contacts 51—55 is selected so as to afford the engineer reasonable latitude in the manipulation of this contactor, but is short enough to prevent the engineer from acknowledging by one act two successive signals or control points.

Unless the speed of the train at the time the relay S is deenergized is below the mini-

mum speed, so that the contacts 40 are closed and together with wires 85 and 86 establish a shunt around the front contact 74 of the relay S, the engineer must either have his 5 brake valve in the service position, or must have made the required reduction in equalizing reservoir pressure, otherwise the stick circuit for the relay Q is interrupted, the brakes are applied and the reset switch RS 10 must be operated from the ground before the train can proceed. If the engineer has his brake valve in the service position, a multiple path or shunt around the front contact 74 of the relay S is established by wire 87, contacts 41, and wire 88; and similarly, if a pre-determined reduction has been made in the 15 equalizing reservoir pressure, closing contacts 48, a like multiple path or shunt is established through wire 89 contacts 48 and wire 90.

20 By reason of the construction and arrangement just described, the engineer is compelled to reduce the speed of his train, unless below the minimum speed, after passing the caution track magnet, with the result that 25 the train is safely controlled. It will be observed that if the engineer should move his brake valve out of the service position before making sufficient reduction in equalizing reservoir pressure to close contacts 48, or 30 should attempt to release the brakes after closure of these contacts, which would immediately open upon movement of the engineer's brake valve to the release or running positions, the relay Q would be deenergized, 35 since the front contact 74 of the relay S remains open thruout the caution block.

Acknowledgment at a stop signal.—For reasons already explained, it is considered important to require the engineer to acknowledge 40 each stop signal. This is done by automatically applying the brakes unless the engineer takes appropriate action. Since such acknowledgement is required to assure safe control of the train in case the engineer is 45 incapacitated, it is considered essential that the point where such acknowledgement is required should be so located that, if no acknowledgement is made and an automatic brake application occurs, the train will be 50 stopped short of the point of danger. For this reason, the track device or magnet T¹ is located braking distance for the minimum speed from the exit end of the block.

55 As the locomotive or car passes the track magnet T¹, which is in the danger condition with the block F occupied, due to the opening of the front contact 26 of the track relay 3¹, the armature 37 of the receiver R is attracted again and the relay P is again momentarily deenergized, such deenergization occurring even though the relay S is deenergized, because the armature 37 breaks the connection to C through the relay P. If at the time of such momentary deenergization 60 of the relay P, and the accompanying open-

ing of its front contact 69, the engineer does not have the plunger of the acknowledging contactor AC depressed, the quick acting relay Q is deenergized and the brakes applied. This automatic brake application occurs even 70 though the running speed is below the low speed limit, and the contacts 40 are closed. The relay Q is, of course, made quick acting so as to open in the interval of time that the armature 37 of the receiver is in the retracted 75 position, it being noted that this time is longer because the speed of the train is low.

The same acknowledgment is required at each successive stop signal, since the relay P is deenergized at each active track magnet. 80 Also, if two track magnets are used in a block, one for caution control and the other for compelling acknowledgment of the stop signal, then the engineer must acknowledge at both of these points. In short, each active initiating track device requires acknowledgement. 85

Reset.—The reset track devices TR are shown as located on the right hand side of the track with respect to the normal direction of traffic. The automatic reversing switch X renders effective the reset receiver RR on the corresponding side of the locomotive, irrespective of which end of the locomotive is ahead, and providing that the locomotive is traveling in the normal direction of traffic. It will be observed that the coil 12 of the reset track magnet TR is energized if the next block in advance is not occupied. 95

90 Assume that a train has passed thru a caution block and that in the meantime the block in advance has cleared up. As the train approaches the entrance to the unoccupied block and passes over the reset track magnet TR which is energized under these conditions, the armature 39 of the corresponding reset receiver is attracted, establishing a pick-up circuit for the relay S, as follows:—commencing at B, armature 39, wire 91 or 92, as the case may be, reset switch 31, wires 93 and 95 66, relay S, wire 67 and front contact 68 of relay P to C. 100

105 Upon reenergization of the relay S the normal stick circuit for the relay Q is re-established, and the train may proceed at its normal running speed without interference. In this connection it will be obvious that, if desired, speed contacts, opening above a selected maximum speed, may be inserted 110 in series with the front contact 74 of the relay S, thereby providing a maximum speed limit. As shown, there is no maximum speed limit enforced under clear traffic conditions. 115

120 In case the engineer fails to acknowledge an active initiating track magnet, or fails to make timely initiating of a manual brake application while exceeding the low speed limit for other than clear traffic conditions, and the relay Q becomes deenergized, it is necessary for the engineer to operate the re- 125 130

set switch RS before the relay Q can again be energized, the brakes released, and the train proceed. Upon operation of the reset switch RS, the closure of its normally open contacts 58 establishes a connection through wire 94 to C in shunt or in multiple with that through the front contact 79 of the relay K, whereupon the relay Q is reenergized. The reset switch RS must, however, be restored to the normal position to reclose its contacts 57, otherwise the electro-pneumatic valve EPV cannot be energized and the brakes released. These contacts 57, therefore, protect the reset switch RS against abuse and prevent it from being carelessly or maliciously left in the operated position.

Briefly summarizing the operation of the system of this invention, it will be observed that acknowledgement is required for each caution signal and for each stop signal, or corresponding control point. In the preferred arrangement of track devices, such as shown in the block E, the acknowledgement of the caution signal takes place at the device T in advance of the signal and at least braking distance for the normal running speed from the exit end of the block; and the acknowledgement of the stop signal occurs at the device T¹ located braking distance for the minimum speed from the exit end of the block. This arrangement requires two initiating track devices for each block, but is considered to be the preferable arrangement for the conditions ordinarily encountered in practice. In the interests of safety, as herein before pointed out, the track device T¹ forcing acknowledgement for the stop signal, should be located in the rear of the signal, and must be effective if the signal is at stop, though not necessarily if the signal is at caution. This same track device T¹ could be used as the cautionary track device, but such an arrangement would have the objection that acknowledgement would be required at a distance in the rear of a caution signal and at a point where the signal might not be readily visible, and also that a speed reduction would be compelled before reaching the caution signal. Regarding the reset magnet, in view of the foregoing explanation of operation it can be seen that this magnet should be located close to the exit end of each block, so that a train will not receive a resetting impulse if there are any cars between the reset magnet and the end of the block. Also, the reset magnet should be in the rear of the cautionary initiating track device, assuming that the reset magnet will be used to clear up the car apparatus at a caution signal as well as at a clear signal, otherwise the initiating impulse received at the cautionary track magnet might be improperly nullified by the reset track magnet. So long as the fundamental principles mentioned and other re-

quirements essential to safety are satisfied, the disposition and location of the track devices and car receivers is susceptible of considerable variation and modification. For example, separate initiating receivers 70 R on opposite sides of the center line of the track may be used and selected by the automatic reversing switch X, the initiating track magnet being of course located and controlled accordingly.

Single track operation.—On single track railroads, trains normally move past signals and control points in both directions, and since the train control system must be capable of safely regulating train movement in either direction, special problems are presented in applying train control systems to single track railroads. Fig. 2 shows one arrangement of track devices and control circuits applied to an intermediate signal location of a single track block signalling system of the well known type commonly termed an A. P. B. system. The circuit arrangements and devices constituting an A. P. B. system are now generally known and recognized in the art, so that detail illustration and description is unnecessary. One specific form of an A. P. B. system is shown and described in detail in the patent to Wight No. 1,294,736, dated February 18, 1919, to 95 which reference may be made for a disclosure of the specific means utilized to obtain the operations and results herein generally explained.

Referring to Fig. 2, the adjacent ends of two blocks K and L are illustrated, these blocks being provided with track relays 98 and 99, respectively. The signal 100, which is of the usual three-position type, governs traffic from left to right, from the block K 100 into the block L; and a similar signal 101 governs traffic in the opposite direction from the block L into the block K. In the A. P. B. system, when a train enters a stretch of single track, all of the opposing signals governing traffic in the opposite position assume the danger or stop position. A train approaching from the left in Fig. 2 and passing from the block K into the block L will, therefore, find the signal 101 at stop, irrespective of the presence of other trains. The signals, such as 100 in the case just assumed, governing traffic in the direction in which the train is running are automatically controlled to the clear, caution, or danger position by the presence of other trains ahead in the same way as on a double track. Associated with each of the signals in an A. P. B. system is a directional stick relay which is normally deenergized and which is automatically energized 110 upon passage of a train by the corresponding signal in the direction of traffic governed thereby. Referring to the signal 100, the stick relay ST 100 is energized when a train, traveling from left to right, passes the signal 115

100, and this relay is maintained energized until the rear end of this train has advanced beyond the next signal ahead governing traffic in the same direction. The other stick relay ST 101 for the signal 101 is controlled in the same way. The particular circuits and devices for thus controlling these stick relays ST 100 and ST 101 are not material to the present invention and have not been illustrated, one arrangement of such control circuits and devices being shown and described in the patent to Wight above mentioned. For simplicity in illustration and explanation, the controls for the track devices have been shown in Fig. 2 as accomplished by the opening and closing of circuit controllers operated in the usual way in accordance with the position of the signal. These circuit controllers are shown in accordance with established convention. There are three circuit controllers for each signal, those for the signal 100 being designated 102, 103 and 104, the corresponding circuit controllers for the other signal 101 being given the same reference numbers with an exponent. Circuit controller 102 is closed only if the signal is in its 90° or clear position. Circuit controller 103 is closed with the signal in the 90° or clear position, or in the 45° or caution position, or any intermediate position between these two. The circuit controller 104 is closed from 90° to 45°, the same as the circuit controller 103.

The cautionary initiating track device T is located at the signals substantially opposite the insulated joints defining the block ends. This track device is disposed midway between the track rails and influences a receiver R on a car passing thereby in either direction. There are two energizing circuits for the neutralizing coils 11 of the track magnet T, these circuits being similar, so that the tracing of one will make both clear. One of these energizing circuits, controlled by the signal 100 may be traced as follows:—commencing at lower coil 11, wire 105, battery 106, wires 107 and 108, back contact 109 of track relay 98 of block K, wire 110, circuit controller 102, wires 111 and 112 back to the other coil 11.

Assuming a train approaching from the left, the opposing signal 101 will be at stop. When the approaching train enters the track section K, the track relay 98 drops and closes its back contact 109; and if the signal 100 is then in the clear position, the neutralizing coils 11 of the track device T are energized and said track device is rendered inactive. If the signal 100 is in the caution or stop position, the circuit controller 102 interrupts the energizing circuit for the coils 11, rendering the track device T active. The same explanation applies for train operation in the other direction, the circuit controller 102' of

the signal 101 controlling the energization of the coils 11 in this instance.

The initiating track device enforcing acknowledgement of a stop signal, as previously explained, is located braking distance 70 for the minimum speed in the rear of the corresponding signal. The track device T¹ for the signal 100 has two energizing circuits for its neutralizing coils 11, one through the back contact 113 of the track relay 98 and through the circuit controller 104 of the signal 100, the other circuit including a front contact 114 of the opposing stick relay ST 101. Assuming a train traveling from left to right, the stick relay ST 101 is deenergized; and when this train enters the track section K and drops the track relay 98, closing its back contact 113, the coils 11 of the track device T¹ are energized, providing the signal 100 is in either the clear or caution position. If the signal 100 is in the stop position, the coils 11 of the track device T¹ are on open circuit, and the engineer must acknowledge. The stick relay ST 101 picks up for a train traveling in the other direction, from right to left, closing its front contact 114 to energize the coils 11 of the track device T¹, irrespective of the position of the signal 100. Consequently, the track device T¹ for the signal 100 is always 95 inactive for a train traveling in the opposite direction, due to the control of the stick relay ST 101. The same explanation applies to the control of the track device T¹ for signal 101. 100

The reset magnets for both directions are controlled in the same way as on double track, except that a back contact 115 of the adjacent track relay is used instead of the front contact of a relay in series with the track battery, and a circuit controller on the signal instead of a front contact of the track relay next in advance. For example, the energizing circuit for the reset magnet TR for traffic moving from left to right in 110 the direction governed by the signal 100 may be traced as follows:—starting at the reset magnet TR, wire 24, back contact 115 of the track relay 98 of the block K, wire 25, circuit controller 103 of the signal 100, wire 115 27, battery 28 and wire 29 back to the reset magnet. The automatic reversing switch X renders the proper receiver on the locomotive effective to cooperate with the correct reset track device. 115

The invention has been disclosed in a simple form, divested of many features of construction and operation that might be desirable in practice; and it should be understood that various expedients may be employed in connection with the specific means herein disclosed to provide for cab signals, train movement against the normal direction of traffic without control, elimination of cab signals and automatic control, with 120 125 130

the giving of a distinctive signal, while in unequipped territory, and the like. Moreover, the invention is not restricted to the particular construction, combination or arrangements of parts and circuits herein disclosed, but is susceptible of wide variation in the particular form of means employed. Various changes, adaptations, additions, and modifications may be made in the particular 10 embodiment of the invention disclosed, without departing from the invention or deviating from the fundamental concept of means underlying the invention.

What I claim is:

15 1. In an automatic train control system, the combination with a traffic controlled track device providing a local magnetic field when in the active stopping condition, an armature on a car attracted by the magnetic field of said active track device, means on the car controlled by said armature and tending to cause an automatic application of brakes on the car, and manually operable means effective only if actuated prior to the 20 attraction of said armature for preventing such application of the brakes.

2. In an automatic train control system, the combination with a track magnet producing an external local magnetic field when 30 in the active stopping condition, of automatic brake control apparatus on a vehicle, control means on the vehicle operated by magnetic attraction while passing through the magnetic field of said track magnet and tending to cause operation of said apparatus, and manually operable means on the vehicle effective for a limited time only after each manual operation and capable of preventing operation of said apparatus only if 35 manually operated prior to the operation of said control means.

3. In an automatic train control system, means on a vehicle including an electro-magnetic valve and acting upon the regular air-brake equipment of the vehicle to produce an automatic brake application upon de-energization of said valve, a stick relay on the vehicle controlling said valve and having a stick circuit including contacts of the relay 45 closed only if said relay is energized, a traffic controlled track magnet producing a local magnetic field under dangerous traffic conditions, an armature on the vehicle attracted by the magnetic field of said track magnet and 50 when attracted interrupting said stick circuit, and manually operable means for maintaining said stick relay energized independently of the break in its stick circuit made by the action of said armature, said manually operable means having a limited time of 55 effective action and being effective only if actuated prior to the attraction of said armature.

4. An automatic train control system for 60 railroads comprising, a track device produc-

ing a local magnetic field when in its active stopping condition, brake control apparatus on a vehicle, impulse receiving means on the vehicle including a relay temporarily de-energized by the influence of the magnetic field of said track device, said relay when thus de-energized tending to cause operation of said brake control apparatus, and manually controllable means including a stick relay for preventing such operation of said brake control apparatus, said manually controllable means being effective only if actuated prior to operation of said apparatus and only for a limited time after each manual operation.

5. In an automatic train control system, the combination with a brake control device effective when active to automatically apply the brakes of a vehicle and maintain such brake application until the vehicle has been brought to a stop, of intermittent inductive impulse transmitting means acting at pre-determined control points along the track to produce initiating and restoring influences on the vehicle in accordance with the presence or absence of other trains ahead, speed control apparatus including a speed responsive device driven from the wheels of the vehicle and rendered effective by said initiating influences to actuate said brake control device if the running speed of the vehicle thereafter at any time exceeds a predetermined low speed limit, said speed control apparatus being restored to normal by said restoring influences, control means temporarily influenced by said initiating influences for tending to actuate said brake control device, manually operable means effective for a limited time for each operation and only if operated prior to the actuation of said brake control device for maintaining it inactive in spite of its control by said control means, and other manually controllable means for maintaining said brake control device inactive in spite of said speed control apparatus only so long as the engineer is initiating a manual brake application or is maintaining a completed 100 brake application.

6. In an automatic train control system for railroads having tracks divided into blocks, a track magnet near the exit end of each block at braking distance for a predetermined low speed from the exit end of said block, each track magnet comprising a permanent magnet and neutralizing coils and producing a local magnetic field if the next block in advance is occupied, brake control apparatus on the vehicle tending to produce an automatic brake application at the time of movement of the vehicle past an active track magnet, and manually operable means effective only if actuated prior to the operation of said apparatus for preventing such brake application, said manually operable means being effective for a limited time only after each manual operation thereof.

7. In an automatic train control system for railroads having tracks divided into blocks, a track device associated with each block and assuming an active stopping condition if the 5 next block in advance is occupied, brake control apparatus on a vehicle including a speed responsive device driven from the wheels thereof, impulse receiving means on the vehicle responding to said track devices when 10 in their active stopping condition for rendering said brake control apparatus effective to apply the brakes automatically whenever the speed of the vehicle exceeds a predetermined low speed limit, said apparatus including a 15 stick relay which if de-energized produces a brake application that cannot be released until the vehicle has been brought to a stop, a normally open energizing circuit for said stick relay, and manually operable means for 20 closing said circuit for a limited time only, said manually operable means being effective only if actuated prior to the reception of an impulse by said impulse receiving means.
8. Car apparatus for train control systems 25 comprising, brake control apparatus including an electro-pneumatic valve for automatically applying the brakes on de-energization of said valve, a normally energized stick relay maintaining said valve energized, a stick 30 circuit for said relay, separate circuit controlling devices for interrupting said stick circuit, one of said circuit controlling devices being temporarily opened in response to control influences from the trackway, the other 35 of said circuit control devices being maintained open so long as dangerous traffic conditions exist, manually operable means for establishing a shunt around the first circuit controlling device for a limited time, and 40 other manually operable means for maintaining a shunt around the other of said circuit controlling devices only so long as the engineer is initiating or maintaining a manual 45 brake application.
9. In a train control system for single track railroads, equipped with an absolute-permissive-block system of the character described, the combination with a signal governing traffic in one direction, of a track device opposite said signal and located symmetrically on the center line of the track, a control circuit for said track device acting when closed to render it inactive, means operated in accordance with the direction and movement of 50 trains by said signal for opening said control circuit when a train approaches said signal in the direction of traffic governed thereby and there is another train in advance, a reset track element located on one side of the center 55 line of the track and in the rear of said signal, and means for rendering said second track element active irrespective of the direction of train movement if the track in advance of said signal and protected thereby is un- 60 occupied.
10. In an automatic train control system for single track railroads equipped with an absolute-permissive-block signal system, the combination with an intermediate signal, of a track element for governing traffic in both directions, and a reset track element capable of cooperating with trains moving in the direction of traffic governed by said signal only, and automatic means for governing and controlling the condition of track elements in 65 accordance with traffic conditions.
11. A train control system for single track railroads comprising, in combination with the intermediate signals of an absolute-permissive-block system, of a reset track magnet for each signal located one side of the center line of the track, control means for each reset magnet and energizing it if the portion of track in advance of the corresponding signal and protected thereby is not occupied, a railway vehicle carrying receiving devices on opposite sides each capable of cooperating with the reset magnets on opposite sides of the track, train control apparatus on the vehicle, and automatic means operated from the running gear of the vehicle for connecting said train control apparatus to the receiving device on that side of the vehicle on which are located the reset magnets associated with the signals that govern traffic in the direction the 70 vehicle is then running.
12. In a train control for single track railroads equipped with an absolute-permissive-block signal system, the combination with the intermediate signals of said block signal system, of a reset track element for each signal, active if the portion of track in advance thereof and protected thereby is unoccupied, initiating track elements adjacent said signals, means responsive to the direction of the train movement for governing the controlling condition of each initiating track element in accordance with the presence or absence of trains in advance of the associated signal 75 when a train approaches said signal in the direction of traffic governed thereby, a vehicle equipped with brake control apparatus having its operation dependent upon the running speed of the train, a receiver carried by said vehicle in position to cooperate with the initiating track element irrespective of the direction in which said vehicle moves past said element, separate reset receivers carried by the vehicle and cooperating selectively with the reset track elements of the signals governing traffic in opposite directions, and automatic means on the vehicle for operatively connecting one or the other of said reset receivers, to the brake control apparatus on the vehicle in accordance with the direction of rotation of the wheels of the vehicle.
13. In a train control system for railroads divided into blocks, a trackway impulse device comprising a magnetic core in the coil located in each block near the exit end there-

of braking distance for a predetermined low speed from said exit end, brake control apparatus on a vehicle including a speed responsive device driven from the wheels thereof and acting when rendered active to automatically apply the brakes if the running speed of the vehicle at any time exceeds said predetermined low speed, an impulse receiver on the car cooperating with said trackway impulse device for rendering said apparatus active, means governed by said impulse receiver intending to automatically apply the brakes independently of speed for a limited time at each active trackway impulse device, 15 a manually operable acknowledging device on the vehicle effective for a limited time and only if operated prior to the reception of said impulses for preventing the brake application by said means, and means for automatically restoring said apparatus to normal and remove the low speed limit at the entrance to each unoccupied block.

14. A train control system of the intermittent inductive type comprising, trackway and car-carried apparatus cooperating to apply the brakes irrespective of the speed of the car at a predetermined control point at braking distance for a low speed limit in the rear of each stop signal, a manually operable 25 acknowledging device effective to forestall such brake application, provided it is operated prior to such brake application, said acknowledging device being effective for a limited interval only when maintained in its 30 operated condition, and brake control means including a speed-responsive device driven from the wheels of the car and governed by said trackway and car-carried apparatus to establish a restricted speed limit which the 35 car cannot exceed without an automatic application of the brakes, said manually operable device being ineffective to prevent such brake application due to excessive speed.

15. A controlling element for train control 45 systems comprising a circuit controller, and means for operating said circuit controller including two diaphragms, one of said diaphragms being exposed to the action of a spring and the pressure in the equalizing 50 reservoir of the usual air brake system, and the other diaphragm being exposed to a feed valve pressure corresponding to the normal running brake pipe pressure.

16. In an automatic train control system 55 for railroads having track divided into blocks, a track magnet near the exit end of each block braking distance for a predetermined low speed from the exit end of said block, each track magnet producing a local magnetic field 60 if the next block in advance is occupied, a normally energized relay on the vehicle temporarily de-energized by the influence of the magnetic field of a track magnet in its active condition, brake control apparatus upon the 65 vehicle, said relay upon de-energization

thereof tending to actuate said apparatus, said apparatus when once actuated to apply the brakes being maintained in that condition and preventing release of the brakes until restored, means for restoring said apparatus 70 after the vehicle has been brought to a stop, and manually operable means effective only if actuated prior to the operation of said apparatus for preventing such brake application, said manually operable means being effective 75 for a limited time only after each manual operation thereof.

17. In an automatic train control system for railroads having tracks divided into blocks, an impulse transmitting device on the track near the entrance end of each block, a second impulse transmitting device near the exit end of each block at braking distance for a low speed from said exit end, a control circuit for rendering each of said trackway devices ineffective and closed only if the block in advance of the block in which said device is located is then unoccupied, receiving means on the car including a relay temporarily de-energized by the influence of said trackway device in its active condition, brake control apparatus on the car, said relay when de-energized tending to cause operation of said apparatus and apply the brakes, manually operable means effective for a limited time only after each operation thereof and also only if operated prior to the actuation of said apparatus by said relay, for preventing such operation of said apparatus, another relay on the car de-energized by said first mentioned relay, and maintained de-energized until restored, mechanism on the car including a speed-responsive device driven from the wheels thereof and rendered effective upon de-energization of said another relay for tending to cause operation of said brake control apparatus if the car exceeds said low speed, and impulse transmitting means partly on the car and partly along the track effective 90 near the exit end of each block for restoring said another relay to its normal energized condition provided the next block in advance is then unoccupied.

18. In an automatic train control system for railroads having tracks divided into blocks, a tripping impulse device on the track near the entrance to each block and automatically controlled to assume its active stopping condition if that block or the next block 105 in advance is then occupied, a reset impulse device near the exit end of each block and automatically controlled to assume its active condition only if the next block in advance is not occupied, impulse receiving means on a vehicle including a relay momentarily de-energized by said tripping impulse device in its active stopping condition, a second relay on the vehicle also de-energized by said tripping impulse device in its active stopping condition, said second relay when de-energized 110

remaining in that condition until restored by an active reset impulse device on the track, brake control apparatus on the vehicle governed jointly by said relays and including a speed-responsive device driven from the 5 wheels of the vehicle, said apparatus acting while said second relay is de-energized to permit movement of the vehicle without an automatic brake application only at speeds less than a predetermined low speed limit, 10 said first mentioned relay when de-energized tending to actuate said apparatus independent of the running speed of the vehicle, and manually operable means on the vehicle effective 15 only for a limited time after each operation and only if actuated prior to the operation of said brake control apparatus for temporarily preventing operation of said apparatus by de-energization of the first relay, 20 said manually operable means being ineffective to prevent operation of said apparatus upon de-energization of the second relay.

19. Car-carried apparatus for automatic train control systems comprising, an air brake system including an engineer's brake valve, 25 an equalizing reservoir, and a source of fixed pressure; a normally energized brake control device adapted when de-energized to act on said air brake system and cause an automatic 30 brake application which cannot be released until the car has been brought to a stop, an energizing circuit for said device including three branches in multiple, contacts in one branch automatically opened and closed by 35 controlling impulses from the trackway in accordance with traffic conditions, speed-responsive means driven from the wheels of the car for opening a second branch of said circuit if the running speed of the car at any time 40 exceeds a predetermined speed limit, and means for closing the third branch of said circuit provided said engineer's brake valve is in a brake applying position or the pressure in the equalizing reservoir has been reduced a predetermined amount less than said 45 fixed pressure.

20. Car-carried apparatus for automatic train control systems comprising, an air brake system including an engineer's brake valve, 50 a fluid pressure operated circuit controller coupled to said air brake system and closed only if a brake application of a predetermined intensity is acting, a normally energized electro-pneumatic valve adapted when 55 de-energized to act upon said air brake system and cause an automatic brake application, a normally energized stick relay controlling said valve, means effective only after the car has been brought to a stop for restoring 60 said stick relay after de-energization thereof, a stick circuit for said relay including two branches in multiple, a speed-responsive device driven from the car wheels having contacts for closing one of said branches only 65 so long as the car is running at a speed less

than a predetermined speed limit, means controlled from the trackway in accordance with traffic conditions for opening and closing a shunt circuit around said contacts of the speed-responsive device, and means for closing the other branch comprising contacts on the engineer's brake valve closed only in its 70 brake applying positions in multiple with said circuit controller, whereby the car may run at speeds above said speed limit provided the engineer has moved his brake valve to a 75 brake applying position or has manually applied the brakes to a predetermined extent before said speed limit was exceeded.

In testimony whereof I affix my signature. 80
